United States Patent Office

Des. 202,120
Patented Aug. 31, 1965

202,120

STOCKING

Curt Seifart, Charlotte, and Avery D. May, Shelby, N.C., assignors to Hudson Hosiery Company, Charlotte, N.C., a corporation of North Carolina

Filed Nov. 23, 1964, Ser. No. 82,749

Term of patent 14 years

(Cl. D47—7)

FIG. 2

FIG. 1 is a side elevational view of a stocking embodying our new design with the opposite side of the stocking being the same as that shown; and

FIG. 2 is a greatly enlarged portion of the fabric shown in FIG. 1.

We claim:

The ornamental design for a stocking, as shown.
